US00D619252S

(12) **United States Design Patent**
Way et al.

(10) **Patent No.:** **US D619,252 S**
(45) **Date of Patent:** ** *Jul. 6, 2010

(54) **TISSUE MODIFICATION DEVICE**

(75) Inventors: **Bryce Way**, San Jose, CA (US); **Alberto Cantu**, San Francisco, CA (US); **Minh Tran**, Fountain Valley, CA (US)

(73) Assignee: **Vertos Medical, Inc.**, Alico Viejo, CA (US)

(*) Notice: This patent is subject to a terminal disclaimer.

(**) Term: **14 Years**

(21) Appl. No.: **29/326,737**

(22) Filed: **Oct. 23, 2008**

(51) **LOC (9) Cl.** **24-02**

(57) **CLAIM**

We claim the ornamental design for a tissue modification device, as shown and described.

DESCRIPTION

FIG. 1 is a perspective view of the tissue excision device of the present invention showing the new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a bottom perspective view thereof;

FIG. 9 is an enlarged rear perspective view thereof; and,

FIG. 10 is an enlarged fragmentary view of the distal tip thereof.
